UNITED STATES PATENT OFFICE.

JAMES C. SHULTS, OF MEADVILLE, PENNSYLVANIA, ASSIGNOR TO RUSS AUTOMATIC LABELING CO., A CORPORATION OF DELAWARE.

SHEET SEPARATING AND FEEDING MECHANISM.

1,285,432.

Specification of Letters Patent. Patented Nov. 19, 1918.

Original application filed April 17, 1915. Serial No. 21,947. Divided and this application filed January 24, 1916. Serial No. 74,011.

To all whom it may concern:

Be it known that I, JAMES C. SHULTS, a citizen of the United States, residing at Meadville, in the county of Crawford and State of Pennsylvania, have invented certain new and useful Improvements in Sheet Separating and Feeding Mechanism, of which the following is a full, clear, and exact specification.

10 This invention relates to sheet separating and feeding mechanism and has particular reference to a means for feeding sheets one by one from a pile, the sheets after being separated being used as labels, or to be printed upon, or for any other purpose wherein separated sheets are to be further handled.

This application is a division of application filed April 17, 1915, Serial No. 21,947.

20 By this invention, the labels or sheets are fed from the top of a pile by a novel separating mechanism, and in order to insure that the labels will be fed singly, the pile is automatically maintained at a given level.

25 In the accompanying drawing, Figure 1 is an elevation of a mechanism embodying the invention, and

Fig. 2 is a plan view.

Referring now to Fig. 1, the sheets or labels 15 are stacked on a vertically movable support 16, which support carries a vertical rack 17, which is automatically lifted so as to keep the top of the pile of labels always at a predetermined level. A spring motor 36 mechanism is preferably used for this purpose, the spring motor being of any usual or well-known construction consisting of a winding shaft 26 geared to shaft 19, the latter having a ratchet 20 and pawls 21. The

40 spring is shown on shaft 26. The shaft 19 carries a pinion 23 which is geared to a larger gear 24 which is turned by a pinion 25 on shaft 26 by handle 27. By turning handle 27 in the direction of the arrow, the

45 spring shaft 26 is wound up. The arrows in Fig. 1, show the directions of rotation as the spring unwinds to feed up the label support. To control the unwinding of spring shaft 26, an escapement mechanism is pro-

50 vided which consists of a large gear 28 on shaft 19 which meshes with a pinion 29 on shaft 30 which carries a gear 31 which meshes with a similar pinion 32 on shaft 33. The shaft 33 carries a gear 34 which drives a

55 small pinion 35 which carries a flier 36.

This gearing very considerably multiplies the revolutions of flier 36 from shaft 26, which through pinion 23 and gear 24 is geared to the rack 17 through gear 38. When the flier 36 is prevented from turning, as by rod 39, the entire train of gearing is 60 stationary, and thus the label support 16 is held stationary. When the spring is wound up, the support 16, through gears 25, 38 and rack 17 is lowered.

The rod 39 is mounted at the top of the machine above the labels on a rock shaft 40, and this rock shaft carries an arm 41 provided with a roller 42 which rests on the top label. When the roller 42 drops sufficiently, 70 the end of rod 39 will be thrown downwardly clear of flier 36 and thus flier 36 will rotate and through the reduction gearing to gear 38 will gradually lift the rack 17 and the pile of labels until the end of rod 75 39 again comes in the path of the revolving flier 36. By suitable adjustments, this mechanism can be made so delicate that the pile of labels will automatically be fed upwardly as each one is withdrawn.

80 The sheet or label separator comprises a cross head 45, which reciprocates on guides 46, being operated from shaft 48 by pitmen 49. The cross head 45 carries two pivots 50, between which is mounted an arm 51 carrying rubber rollers 52 which bear on the top label. These rollers are rotatably mounted in the arm 51, but are held from rotating backwardly by a ratchet 53. During the feeding motion, which is the motion to the 90 right in Figs. 1 and 2, the arm 51 and rollers 52 rest on the top label by gravity and pull this top label from the other labels and push it forward into the bite of belts 54. I have found that a mere reciprocatory roller is 95 ineffective to always separate single labels in this manner, but that by providing pins 56 at the rear side of the labels, preferably having inclined edges against which pins the labels are pushed by lifting the support 16, it is absolutely assured that but one label 100 will be fed at a time, even with very thin labels. These pins 56 are adjustably mounted in cross bars 57, and are preferably shaped like a cross section of a knife blade, 105 that is, with the sharp edge pointing rearwardly or to the left so that the label tends to lift up on the inclined edge. The pushing rollers 52, by reason of the engagement of the ratchet 53, simply push the top label 110

only and the knife pins 56 engage a fraction of an inch at the rear end of the label. As soon as the forward end of the label is grasped by the belts 54, the label is pulled bodily forward, and the ratchet 53 yields and permits the rollers 52 to revolve. When the cross head strikes its extreme forward position, the arm 58 on arm 51 strikes a stop 60, lifting rollers 52 off the label and also causing latch 61 to engage and hold the arm 51 and the rollers 52 elevated during the back stroke. At the end of the back stroke the latch 61 is tripped by striking stop 63, thereby allowing the arm 51 and rollers 52 to drop on the next label to push it off the top of the pile upon the next forward movement. The stop 60 and the trip 63 can be made adjustable to suit various lengths of labels. The rollers 52 are adjustable in the arm 51 toward and from the pivots 50 so as to change the angle of thrust through arm 51 with the surface of the label. By adjusting this angle exactly the right thrust can be secured. Stop 63 is pivoted so that it can be turned back, thus preventing tripping of latch 61. This stops the feed of labels without stopping the entire machine.

From the belts 54 the sheet or label is delivered to any desired mechanism, either for printing, gumming, moistening, etc., preparatory to final disposition of the sheet. It is to be understood that while this invention was originally shown in connection with a label applying mechanism, it is not to be restricted thereto, as the mechanism is intended for general sheet separating and feeding purposes.

From the foregoing description, it will be seen that a very accurate and reliable sheet separating and feeding mechanism of novel construction is provided by the foregoing mechanism, and in actual practice, it has been found to reliably and accurately separate and feed sheets where previous mechanisms had failed. Within the scope of the appended claims, various modifications and changes in the specific parts may be made.

What I claim is:—

1. The combination with a movable sheet support, of a rotary escapement device driven at a relatively higher velocity and connected to control the movement of said sheet support to secure minute variations of height, sheet actuated means for holding said escapement, and means actuating said escapement and said support when the escapement is free.

2. The combination with a movable sheet support, of a rotary escapement device driven at a relatively higher velocity and connected to control the movement of said sheet support to secure minute variations of height, sheet actuated means comprising a vibratory device for holding said escapement, and means for actuating said escapement and said support when the escapement is free.

3. The combination with a sheet pile support, of means geared thereto and biased to move said support as the pile varies, a rotary escapement device connected to said gearing to be driven at a multiplied rate, and means for blocking said escapement to stop movement of said pile support.

4. The combination with a sheet pile support, of means geared thereto and biased to move said support as the pile varies, a rotary escapement device connected to said gearing to be driven at a multiplied rate, and sheet controlled means for blocking said escapement to stop movement of said pile support.

5. The combination with a pile support, of means for automatically maintaining the pile level comprising a flier controlled lifting mechanism and a pile actuated flier controller, means for engaging and lifting the top sheet, and a separating and pulling mechanism for the top sheet.

In testimony whereof I affix my signature in presence of two witnesses.

JAMES C. SHULTS.
